PINKING MACHINE

Bernard B. Chester, Kingston, and Otto A. Trnka, Saugerties, N. Y.

Application December 31, 1938, Serial No. 248,838

8 Claims. (Cl. 112—122)

This invention relates to sewing machine attachments and particularly to an improved pinking machine capable of being attached to a standard sewing machine and actuated by the same power which actuates the sewing machine, an object being to provide a construction which is arranged wholly beneath the bed plate of the sewing machine except the pinking head.

Another object of the invention is to provide a simple, positively acting pinking structure arranged beneath the bed of the sewing machine and actuated by power taken from the shuttle shaft.

A further object of the invention is to provide a pinking machine attachment which may be applied to a standard sewing machine and caused to operate simultaneously with the needle of the sewing machine and to be readily thrown out of operation at any time to permit the sewing machine to function in the usual manner.

A still further object of the invention is to provide a construction which will form a top stitching operation at the same time that it performs a pinking operation.

In the accompanying drawings—

Figure 1 is a side view of a standard sewing machine which is known on the market as a Singer 95 Commercial, an embodiment of the invention being shown applied thereto;

Fig. 2 is an enlarged view of the bed plate of the sewing machine shown in Fig. 1, together with an embodiment of the invention applied thereto, certain parts being shown in section for better illustrating the construction;

Fig. 3 is a top plan view showing a part of the bed of the sewing machine in top plan and part of the pinking machine structure;

Fig. 4 is a sectional view through Fig. 3 approximately on the line 4—4;

Fig. 5 is a perspective view of the throat plate shown in Fig. 3;

Fig. 6 is a perspective view of the pinking head and actuating arm therefor;

Fig. 7 is a fragmentary perspective view showing the front part of the pinking lever shown in Fig. 3;

Fig. 8 is a plan view of the structure shown in Fig. 9 with a window broken away for illustrating the location of the pinking line.

Fig. 9 is a section on the line 9—9 of Fig. 8 showing the top layer of cloth folded over and stitched down.

Referring to the accompanying drawings by numerals, 1 indicates a sewing machine having

a bed 2 and an arm 3. The needle mechanism 4 is of the usual type and carries a needle 5 which is adapted to function simultaneously with the pinking head 6, as hereinafter fully described.

From an examination of Figs. 1 and 2, it will be readily seen that the entire construction of the pinking device is beneath the bed 2, except the head 6, which head when not in operation is substantially flush with the top of the throat plate 7. This throat plate is a standard plate 10 except for the aperture 8, as shown in Fig. 5. This aperture is provided with a V-shaped portion 9 and straight portions 10, 11 and 12, whereby the head 6 may freely slide therein and be guided thereby, so that the cutting edges of the head cutter 6' may readily function to secure the desired pinking action. As shown in Fig. 8, the notches 13 indicate the pinking, while the lines 14 indicate stitching which takes place at the same time as the pinking.

From Figs. 1 and 2 it will be observed that the bed 2 of the machine is not cut or weakened in any way but only the depending lug 19 is cut to fit the block 35. It will be seen, therefore, that the invention is really an attachment to a standard machine now in common use whereby top stitching and pinking may be formed at the same time, or either of these operations may be performed independent of the other. While in Figs. 3 and 9, inclusive, a straight seam has been illustrated, it will be evident that the machine will readily operate to apply a circular top stitching and pinking at the same time.

From Fig. 3 it will be observed that the point 15 of the cutter 6' is directly in line with the opening 16 through which the needle passes. It will be seen, therefore, that the pinking action will take place at the same time that the stitching is applied.

As indicated, the sewing machine 1 is provided with a shaft 17 which is adapted to rotate the usual shuttle 18 in connection with the needle 5 to provide the desired stitching. The bed 2 is formed with a depending lug 19 which carries a bearing sleeve 20 for the shaft 17. Lug 19 is partly cut away to accommodate a block 35, as hereinafter described. The pinking device embodying the invention is driven from the shaft 17 through a pinion 21, which is pinned or otherwise rigidly secured to shaft 17 and arranged to be in constant mesh with a gear 22 rotatably mounted on a pin 23. An eccentric or cam 24 is pinned or otherwise rigidly secured to the gear 22 and acts on a roller 25 which is journaled on a pin 26. The pin 26 is carried by suitable

connecting bars 27 and 28 secured to the respective levers 29 and 30. By this arrangement the cam 24 is continually rotated and if roller 25 is in engagement therewith the levers 29 and 30 will be raised and lowered, the lowering action being caused by the cam 24 and the raising action being caused by a spring 31. It will be observed that the spring 31 is held in operative position by a screw 32 having an enlarged head 33 and at the opposite end a threaded portion 34 screwed into a block 35 rigidly clamped to the lug 19 by screws 36 and 37 shown in Fig. 4. Screws 36 and 37 are preferably arranged at an angle to each other whereby the block 35 is not only clamped firmly in place but is braced against lateral movement. It will be noted that the pin or shaft 23 is carried by the block 35. Spring 31 presses at one end against the head 33 and at the other end against an arm 38, which arm 20 has a large aperture 39 through which the screw 32 loosely extends. The spring 31 has a double function—it holds the roller 25 against cam 24 and also holds the cutting member 6' of head 6 against the V-shaped wall 9.

25 From Fig. 7 it will be observed that the levers 29 and 30 are connected by a bar 40 which may be integral with the levers or rigidly secured thereto in any way so as to space the threaded enlargements 41 and 42. Binding screws 43 and 44 are fitted into the enlargements 41 and 42, as shown in Fig. 4, and also extend into cone-shaped recesses in the bearing or enlargement 45 of a lever 46. As the cam 24 rotates it will act on roller 25 and swing the levers 29 and 30 downwardly and will pull the lever 46 downwardly to the position shown in Fig. 2. When the cam 24 moves to the opposite position, the spring 31 will raise the levers 29 and 30 and also lever 46 to the position shown in Fig. 1.

40 It will be readily seen, therefore, that the pinking operation will take place while the needle 5 is functioning or, if desired, the needle 5 could be eliminated and the pinking operation carried on. Also, if desired, the hand actuated arm 48', 45 which is rotatably mounted on shaft 47, could be swung upwardly, as shown in Fig. 2. When this occurs the arm 48, which is also rotatably mounted on shaft 47 and rigidly secured to arm 48', will be swung downwardly to the dotted 50 position shown in Fig. 2 and, consequently, levers 29 and 30 will be held in their lowered position, whereby the cam 24 though rotating will not function to actuate the pinking mechanism. This will allow the sewing machine to be used in the 55 usual way the same as if the pinking machine attachment were not applied to the sewing machine. It will also be noted that when the head 6 is in its lowered position the entire bed is clean and clear so that no obstructions will be 60 presented when the sewing machine is being used in the usual way of sewing machines. Also no oil or obstructions will be presented to injure in any way the fabric being stitched or pinked.

65 In regard to the levers 29 and 30, it will be seen that the end opposite lever 46 is pivotally connected to the bracket 49 by a pin 50. The bracket 49 is secured to the bed 2 by screws or bolts 51 which are part of the sewing machine 1. It will 70 be observed, therefore, that no changes are necessary in the sewing machine except the substitution of the throat plate 1 and the application of the screws 36 and 37 and the bracket 52 which mounts the shaft 47 on the lower part 75 of the bed plate. Incidentally it will be ob-

served that the bracket 52 is held in place by suitable screws 53 and 54.

From Figs. 1 and 2 of the drawings it will be seen that the arrangement is such that the machine will top stitch and pink at the same time. 5 If two pieces of cloth were arranged in the machine, as shown in Figs. 8 and 9, the pinking head 6 would perform the pinking operation at the same time the needle 5 performed the top stitching operation. It will, therefore, be seen that 10 the top stitching and the pinking operation is done at one time. From Fig. 9 it will be seen that in the operation illustrated there are three separate layers of cloth which are stitched together at the same time, and two of the layers 15 are pined simultaneously with the stitching operation. Once through the machine and there is produced a completed or finished product.

We claim:

1. A pinking attachment for sewing machines 20 including a construction arranged beneath the bed plate of the sewing machine, except the pinking head and the throat plate, said construction including said throat plate having a V-shaped notch formed so that the walls of the notch 25 will present shearing members, and a pinking head having a V-shaped portion formed with shearing walls coacting with the shearing walls of said throat plate, a lever for moving said pinking head upwardly and downwardly, means 30 driven by the driving mechanism of the sewing machine for moving said lever and pinking head downwardly whereby the pinking head will function in time with the needle of the sewing machine, and spring means for moving said lever and pinking head upwardly. 35

2. A pinking attachment for sewing machines including a construction arranged beneath the bed plate of the sewing machine except the pinking head and the throat plate, said throat plate 40 having an opening with a V-shaped portion, a pinking head fitting into said opening and coacting with the V-shaped portion for cutting a fabric, a reciprocating member for reciprocating said head, a lever wholly beneath said bed plate 45 pivotally mounted at one end and at the opposite end being pivotally connected with said reciprocating member, a spring for moving said lever and said reciprocating member in one direction, a roller carried by said lever, a cam acting on 50 said roller for moving the same against the action of said spring, and a train of gears for transmitting power from the driving mechanism of said sewing machine to said cam for rotating the same. 55

3. A pinking attachment for sewing machines including a throat plate having an opening formed with a V-shaped portion, a reciprocating head slidably mounted in said opening and conforming to the shape thereof, means arranged 60 beneath the bed of the sewing machine for reciprocating said pinking head and means for rendering the pinking mechanism inoperative and for holding said head substantially flush with the top of said throat plate when the pinking 65 mechanism is not functioning.

4. A pinking attachment for sewing machines, said attachment having a throat plate provided with an opening formed with a V-shaped portion, a pinking head slidably mounted in said 70 opening and conforming to the shape of the opening, a reciprocating member connected to said head for actuating the same, a lever pivotally mounted at one end on a fixed member and at the other end on said reciprocating member, 75

means including a rotatable cam for swinging said lever in one direction, and a spring for moving the lever in the opposite direction whereby said pinking head is adapted to reciprocate, and means actuated by the shuttle shaft of the sewing machine for rotating said cam whereby said pinking head will function in time with the needle of the sewing machine.

5. A pinking attachment for sewing machines including a throat plate having an opening provided with a substantially V-shaped portion, a pinking head slidably mounted in said opening and conforming to the shape thereof, means arranged beneath the bed plate of the sewing machine for reciprocating said head, said means being operatively connected to the shuttle shaft of the sewing machine for causing the head to function in timed relation with the needle of the sewing machine, and a hand-actuated lever for throwing said mechanism out of operation and for holding said pinking head substantially flush with the top of said throat plate.

6. A pinking attachment for sewing machines including a throat plate having an aperture therein, a pinking head slidingly fitted into said aperture and conforming to the shape thereof, a reciprocating member for reciprocating said head, a lever structure pivotally connected at one end with the bed plate of said sewing machine, means for pivotally mounting said reciprocating member on the free end thereof, a block rigidly secured to said bed plate, a spring acting on said reciprocating member tending to swing the same in one direction, a headed screw causing said spring to function, said headed screw being carried by said block whereby the reciprocating member and lever will be moved in one direction by said spring, a roller carried by said lever, a cam acting on said roller for moving the lever against the action of said spring and thereby lowering said head, a gear wheel rotatably mounted on said block rigidly secured to said cam, and a pinion rigidly secured to the shuttle shaft of the sewing machine continually meshing with said gear wheel whereby said pinking head will function in time with the needle of the sewing machine.

7. A pinking structure adapted to be connected to a sewing machine with all parts beneath the bed plate thereof except the throat plate and the pinking head, said structure including a bracket connected to said bed plate, a pair of

levers pivotally mounted on said bracket, a reciprocating member pivotally connected to the free end of said levers, said reciprocating member at one end having an apertured arm, a pinking head connected to the opposite end of said reciprocating member, a throat plate having an opening accommodating said pinking head, a block secured to the under surface of the bed plate of said sewing machine, a screw having a head, said screw being threaded into said block and extending through the apertured arm of said reciprocating member, a spring surrounding said screw and acting against the head thereof and said arm, whereby said pinking head is held in functioning position and said reciprocating member and said levers are urged in a direction for raising said head, means including a cam for swinging said levers to lower said pinking head and a train of gearing for rotating said cam, said train of gearing including a pinion rigidly secured to the shuttle shaft of the sewing machine.

8. A pinking structure adapted to be connected to a sewing machine with all parts beneath the bed plate thereof except the throat plate and the pinking head, said structure including a bracket connected to said plate, a lever structure pivotally mounted on said bracket, a reciprocating member connected to the free end of said lever structure, said reciprocating member at one end having an apertured arm, a pinking head connected to the opposite end of said reciprocating member, a throat plate having an opening accommodating said pinking head, a block secured to the under surface of said bed plate, a screw having a head, said screw being threaded into said block and extending loosely through the apertured arm of said reciprocating member, a spring surrounding said screw and acting against the head thereof and said arm whereby said pinking head is held in functioning position and said reciprocating member and said lever structure are urged in a direction for raising the head, and means operated by the driving mechanism of the sewing machine for actuating said reciprocating member and pinking head in time with the needle of the sewing machine whereby the top stitching and pinking may be performed at the same time with the same driving mechanism.
